C. DELAYGUE

REFRIGERATING APPARATUS

Filed March 25, 1924

1 Inventor
Charles Delaygne
By Robert Robert Hill
Attorney

UNITED STATES PATENT OFFICE.

CHARLES DELAYGUE, OF PARIS, FRANCE.

REFRIGERATING APPARATUS.

Application filed March 25, 1924, Serial No. 701,756, and in France November 24, 1923.

This invention relates to improvements in refrigerating apparatus of that character known as the reversing absorption type, and it has for its primary object to provide 5 a very simple, easily operated, and inexpensive construction such that it may be readily adapted for domestic purposes.

With these and other objects in view the invention consists in certain novel features 10 of construction as will be more fully described and particularly pointed out in the appended claims.

In the accompanying drawing:

Figure 1 is a side elevation of the refrigerating apparatus forming the subject matter of this invention, portions thereof being broken away and shown in section to more clearly disclose the details of construction; and

Figure 2 is a top plan view of the generator section of the apparatus.

Like reference characters designate corresponding parts on the several figures of the drawing.

Referring to the drawings and specifically describing the invention, A designates a still-absorber or generator and G a condenser, the specific construction of which latter need not be given as it forms the subject matter 25 of a companion application constituting a division hereof. The generator and condenser just referred to are connected together by an inverted substantially V-shaped conduit R—C which is suitably braced by 30 means of the brace member E. The return section R of this conduit extends into the generator chamber and terminates adjacent the bottom thereof as indicated at R'.

Extending upwardly from the dome or 40 upper portion of the generator chamber is a gas outlet pipe t which communicates with the conduit R—C at the apex of the same. It will be observed that the outlet pipe t projects to a slight extent into the conduit 45 R—C, as indicated at d, the object of the inward extensions being to prevent the passage into the outlet pipe of the liquefied gases during the operation of the apparatus.

The outlet pipe t is provided with a ball 50 valve S, and within the said outlet pipe is suspended a baffle device a constituting a dehydrator in the functioning of the apparatus. This baffle device includes a series of baffle members b spaced from each other, the 55 lower baffle element being disposed adjacent to the ball valve S hereinbefore referred to

and constituting a stop for said ball when the latter is thrown from its seat during the generation of the gas in the operation of the absorber. The generator chamber is 60 preferably provided with a tube which constitutes a thermometer holder or a holding device for a similar temperature indicator.

In the operation of the apparatus the gas is generated in the chamber A in the usual 65 manner by boiling of the ammonia aqueous solution and intermittently passes by way of the outlet pipe t into the inverted V-shaped conduit R—C, where it descends the branch C to the condenser G. In the latter the gas 70 is liquefied in the usual well known manner. In the subsequent phase of operation the gas is re-vaporized and passes by way of the branches C and R back to the generator A 75 where it is absorbed.

In the movement of the gas from the boiler or generator A through the outlet pipe t the water content thereof impinges upon the baffle elements b which are arranged in staggered relation preferably and thereafter 80 trickles downwardly to the base of the outlet pipe from where it returns to the generator chamber A during those moments of time when the ball valve is displaced from the valve seat. It will thus be seen that the gas 85 reaches the condenser G in substantially dry form. When in the use of the apparatus the liquefied gas collects in the condenser G it is possible to return it to the generator by laying the apparatus upon its side so that 90 it will rest upon the laterally projecting lugs O, this position causing the liquid to pass by way of the conduit R—C into the generator A.

From the foregoing it will be apparent 95 that a simple apparatus is provided, the capacity of which is determined by the size of the construction, substantially speaking.

Having thus described my invention, what I claim as new and desire to secure by Letters Patent is:

1. In a refrigerating apparatus of the class described, the combination of a generator, a condenser, a gas conduit connecting said generator and condenser, a gas outlet pipe extending upright from the generator and communicating with the gas conduit, a baffle device suspended from the gas conduit within the gas outlet pipe and constituting a dehydrator, and valve means arranged 105 proximate the entrance to said outlet pipe and adjacent the baffle device aforesaid.

2. In refrigerating apparatus of the class described, the combination of a generator, a condenser, a gas conduit extending from the condenser to the generator and into the latter to a point adjacent the base thereof, a gas outlet pipe extending vertically from the dome of the generator and communicating with the gas conduit aforesaid, a baffle device arranged in said outlet pipe and comprising a support mounted upon the gas conduit, and a series of baffle members arranged in spaced relation on said support, valve means in said outlet pipe, and means projecting from the generator constituting supporting rests for sustaining the refrigerating apparatus on its side during displacement of liquefied gas from the condenser. 15

CHARLES DELAYGUE.
